MARKING IMPLEMENT

Fred A. Sturm, Paterson, N. J.

Application October 26, 1940, Serial No. 362,959

6 Claims. (Cl. 120—43)

This invention relates to marking implements and, more particularly, to improvements in marking implements which contain a viscous marking substance therein for marking textiles or like materials.

Marking instruments of this type, in the past, comprised a tubular container of non-elastic material from which the marking fluid was squeezed, which deformed the container as the fluid was used, making the marking tube difficult to use, particularly after a substantial amount of fluid was squeezed therefrom. The tube would often break and leak, causing the goods being marked and the operator's hands to become soiled.

In my United States Patent, Serial Number 321,463, filed February 29, 1940 and issued June 18, 1940, and bearing Number 2,204,778, I provided a marking implement which successfully overcame the disadvantages of earlier marking tubes. My present invention is an improvement upon the invention of my above patent.

It is an object of the present invention to provide a marking implement which acts as a container for a viscous marking substance, which implement will retain its original shape as the substance is used thereby providing an instrument which may at all times be easily gripped by the operator.

Another object is to provide a marking instrument having an outer body portion of elastic material having therein an inner container of substantially non-elastic material for containing a viscous marking fluid, which marking instrument may be easily, quickly and inexpensively assembled.

A further object of this invention is to provide a marking instrument having an outer body portion of elastic material and an inner container of non-elastic material for holding a viscous marking fluid, wherein the inner container may be easily removed when empty and quickly replaced by a full one.

Another object of this invention is to provide a marking instrument having an outer body portion of elastic material and an inner container of substantially non-elastic material for holding a viscous material in which the marking head may be attached directly to the inner container to hold the same tightly within the outer body portion.

Other objects of this invention will become apparent in the course of the following specification.

The above and other objects of this invention are accomplished by providing a collapsible elastic

tubular casing, a tubular container of substantially non-elastic material constituting a container for a marking substance positioned within said casing and having an externally threaded neck projecting outwardly of the casing, a discharge member adapted to be positioned on the threaded neck and drawn tightly against the casing and hold said tubular container tightly within said casing, a combined marker and closure for the discharge member movably mounted therein and retractable in writing position and means for yieldingly holding the marker and closure in a projected closed position, so that upon the application of pressure to said casing by the writer the shape of both the casing and container is deformed forcefully emitting the marking material from the container past the marker, which is in a retracted position when the implement is in writing position, the casing upon the release of pressure returning to its normal condition but the container remaining in its compressed condition, preventing air being drawn into the container and hardening the marking fluid.

The invention will appear more clearly from the following detailed description when taken in connection with the accompanying drawing, showing, by way of example, a preferred embodiment of the invention.

Referring to the drawing:

Figure 1 is a side elevational view of the marking implement of this invention, partly in section;

Figure 2 is a section taken on the line 2—2 of Figure 1;

Figure 3 is a detailed view of the head of the marking implement of this invention, partly in section;

Figure 4 is a sectional view taken on the line 4—4 of Figure 1.

Like numerals refer to like parts throughout the several views.

The marking implement of this invention comprises a tubular outer casing 10 of an elastic material, preferably of rubber, of sufficient thickness to, under normal conditions, maintain its shape. One end of said casing 11 is open and adapted to be sealed closed by cement, a clip, or any other desired means. The opposite end 12 has an opening 13 therethrough.

Within the casing 10 is a container tube 14 of slightly less diameter than the casing, said container tube being of a non-elastic material such as tinfoil, lead-foil, or like material, the bottom of said tube being closed by the strip 15, the top of the container tube 14 having a bevelled shoulder 16.

portion adapted to abut against a bevelled shoulder portion 17 within the casing 10.

Projecting from the shoulder portion 16 of the tube 14 is a neck 18 adapted to project outwardly from the casing 10, when the shoulder 16 is in abutment with the shoulder 17 of the casing 10. The neck 18 has a passage 19 therethrough which is in communication with the interior of the tube 14. The external surface of the neck 18 has thereon screw threads 20. The screw threads 20 are adapted to receive a cap 21 which has a conical shaped head 22 with a chamber 23 therein.

An orifice 24 is in the apex of the conical head 22 of said cap. A ball 25, which serves as a marking ball, is positioned in the orifice 24. A pin 26, having a head 27, is acted upon by a spring 28, said spring acting to retain the ball in a seated position, the same being positioned between the bottom surface of the head 27 and a washer 29 on top of the neck 18. If so desired, this washer may be dispensed with and a spring having the bottom coil thereof of sufficient diameter to rest upon the top surface of the neck 18 substituted. The pin 26 extends through the spring 28 and into the passage 19.

The casing 10 has vent holes 30 therein through which any air within the casing may be vented when the casing is compressed and through which air may be admitted when the pressure is released from the casing 10.

As shown in Figure 4 of the drawing, the casing 10 has a taper 31 at the bottom thereof, which taper has at the end thereof adjacent extensions 32 and 33 adapted to be spread apart and admit the container tube 14, which extensions may thereafter be sealed by rubber cement, or any other means, as hereinbefore set forth.

In assembling the marking tube of the present invention, it is merely necessary to insert the container tube 14 between the projections 32 and 33, sliding said container tube inwardly until the neck 18 passes through the opening 13 in the opposite end of the casing 10, and the bevelled shoulder 16 of the tube 14 abuts against the bevelled shoulder 17 on the interior of the casing 10.

The washer 29, if one is used, is placed upon the top surface of the screw-threaded neck 18, and the spring positioned on top of the washer. The pin 26 is then inserted through the spring, the washer, and into the passage 19. The ball 25 is positioned in the orifice 24, after which the cap 21, which is screw-threaded internally, is positioned upon the external threads 20 on the neck 18 and screwed downwardly onto said neck until the bottom surface 34 of the cap 21 engages the top surface 35 of the casing 10. Further screwing downwardly of the cap will draw the shoulder 16 of the container tube 14 tightly against the shoulder 17 of the casing 10 and thereby firmly hold the container tube within the casing.

When it is desired to write, the casing 10 is compressed by the operator, which will, in turn, compress the tube 14. The pressure causes the viscous marking fluid to flow through the passage 19 into the chamber 23. The operator may then release pressure from the casing 10, which casing immediately returns to its original, or normal, shape, air being admitted through the vents 30. The container tube 14, however, since it is of a non-elastic material, retains its compressed condition within the casing 10, so that air cannot be drawn back into the container

tube 14 and act upon the viscous marking material, which in most cases is volatile, and harden the same.

In marking a piece of material, the ball 25 is pressed against the same, which depresses said ball against the tension of the spring 28, allowing the marking fluid to flow through the orifice 24.

When the container tube 14 has become empty, if it is desired to remove the same from the casing this may easily and quickly be done by unscrewing the cap 21 from the neck 18 of the container tube 14. If cemented together, the projections are pried apart or if held together by a clip the clip is removed allowing the projections to be spread apart. The container tube 14 is then withdrawn from the casing 10. There are no parts to be removed from a discarded tube, nor are there any parts to be placed within the container tube 14 before it is inserted in the casing. It is merely necessary to screw the cap 21 onto the neck of the container tube over which has been placed the spring 28 and ball 25 which rests upon the pin 26, projecting through the spring and into the passage 19. When the cap 21 is removed the ball 25, pin 26 and spring 28 as well as the washer 29 will fall free of the empty container tube.

It is apparent that the specific illustration shown has been given by way of illustration and not by way of limitation, and that the structure above described is subject to a wide variation and modification without departing from the scope or intent of the invention, all of which variations and modifications are to be included within the scope of the present invention.

What is claimed is:

1. A marking implement having a collapsible elastic tubular casing, a tubular container of substantially non-elastic material for containing a marking substance positioned within said casing and having an externally threaded neck projecting outwardly through an opening in one end of the said casing, a discharge member threaded internally at one end thereof and adapted to be positioned on said threaded neck and drawn tightly against the casing to hold the tubular container firmly within said casing, a combined marker and closure for the discharge member movably mounted therein and retractable in writing position, and means for yieldingly holding the marker and closure in a projected closed position so that upon the application of pressure to said casing the shape of both the casing and container is deformed forcefully emitting said marking substance from said container past the retracted marker when the implement is in writing position, said casing upon release of the pressure returning to its normal condition said container retaining its compressed condition.

2. A marking implement having a collapsible elastic tubular casing having an open end adapted to be closed and an opening through the opposite end, a tubular container of substantially non-elastic material for containing a marking substance positioned within said casing and having an externally threaded neck said tube being adapted to be inserted in the open end of said casing said neck projecting outwardly of said casing through the opening in the opposite end thereof, a discharge member threaded internally at one end thereof and adapted to be positioned on the said threaded neck and drawn tightly against the casing to hold the tubular container firmly within said casing, a combined marker and

closure for the discharge member movably mounted therein and retractable in writing position and means for yieldingly holding the marker and closure in a projected closed position so that 5 upon the application of pressure to said casing the shape of both the casing and container is deformed forcefully emitting said marking substance from said container past the retracted marker when the implement is in writing position, said casing 10 upon release of the pressure returning to its normal condition said container retaining its compressed condition.

3. A marking implement having a collapsible rubber tubular casing comprising walls with air 15 vents therein said walls being of such thickness as to normally retain the body of said casing in tubular shape said casing having one end thereof open and adapted to be sealed closed and a neck on the opposite end thereof with a 20 passage therethrough, a tubular container of slightly less diameter than the inside diameter of said casing said container being of substantially non-elastic material for containing a marking substance adapted to be positioned within said 25 casing through the open end thereof said container having an externally threaded neck projecting outwardly through the passage in the neck of said casing, a discharge member threaded internally at one end thereof and adapted to be 30 positioned on the said threaded neck and drawn tightly against the top surface of the neck on said casing to hold the tubular container firmly within said casing, a combined marker and closure for the discharge member movably mounted therein and retractable in writing position and means 35 for yieldingly holding the marker and closure in a projected closed position so that upon the application of pressure to said casing the shape of both the casing and container is deformed forcefully emitting said marking substance from said container past the retracted marker when the implement is in writing position, said casing upon 40 release of the pressure returning to its normal condition said container retaining its compressed 45 condition.

4. A marking implement having a collapsible elastic tubular casing the walls of said casing be-

ing of sufficient thickness as to normally retain the body in tubular shape, a tubular container of substantially non-elastic material for containing a marking substance positioned within said casing and having an externally threaded neck projecting outwardly through an opening in one of the said casing, and a discharge member threaded internally at one end thereof and adapted to be positioned on said threaded neck and drawn tightly against the casing to hold the tubular container firmly within said casing.

5. A marking implement having a collapsible rubber tubular casing having an open end adapted to be closed and an opening through the opposite end, the walls of said casing being of sufficient 15 thickness as to normally retain the body in tubular shape, a tubular container of substantially non-elastic material for containing a marking substance positioned within said casing and having an externally threaded neck projecting outwardly 20 through an opening in one end of the said casing, and a discharge member threaded internally at one end thereof and adapted to be positioned on the said threaded neck and drawn tightly against the casing to hold the tubular container firmly 25 within the casing.

6. A marking implement having a collapsible rubber tubular casing having an open end adapted to be closed and an opening through the opposite end thereof the inside diameter of said casing 30 being reduced adjacent said opening to form a bevelled shoulder portion within said casing, a tubular container of substantially non-elastic material for containing a marking substance positioned within said casing and having an externally threaded neck projecting outwardly through the opening in said casing the end of said container being bevelled adjacent said neck at substantially the same angle as the bevel in said 35 casing and a discharge member threaded internally at one end thereof and adapted to be positioned on the said threaded neck and drawn tightly against the casing bringing the bevels in said casing and on said container into abutment to hold the tubular container firmly within the 40 casing.
